4 Claims. (Cl. 123—8)

The present invention relates to rotary explosion engines and is concerned with the valve timing-gear of these engines, more particularly the control of the valves, the ignition system and the oil and fuel pumps.

The improvements forming the object of the invention consist essentially in ensuring this control by means of a single cam-shaft.

The valves, which are parallel to the axis of the engine, are located in the combustion chambers formed in the cylinder head which is arranged laterally to the rotor.

In order to take account of the distances of the concentrically-disposed valves from the cam-shaft, the valve push-rods are made of different lengths and the pawls are given different forms.

All the admission cams are given the same profile, and all the exhaust cams have also the same profile in order to facilitate the manufacture of the cam-shaft.

In the accompanying drawings, there has been shown by way of example only, a form of construction of a rotary engine with a rotor having an epicycloidal profile with four teeth, rotating eccentrically in a stator with five teeth which form the envelope of the rotor teeth and comprise five points of contact.

FIG. 1 is a cross-section of the rotary engine, taken in a plane passing through the axis of the engine.

FIG. 2 is a transverse section showing the arrangement of the valve timing-gear members.

FIGS. 3, 4, and 5 show different forms of construction of a device for controlling the valves by pawls, push-rods and rocker-arms, according to the positions of the valves.

Referring now to the drawings, and more particularly to FIG. 1, it can be seen that the rotor 1 has four teeth 2 and rotates eccentrically in a stator having five teeth 4 which form the envelope of the teeth of the rotor.

The rotor 1 is mounted on the eccentric portion 1¹ of the shaft.

The combustion chambers 6 are hollowed out in the cylinder head 5 arranged laterally to the rotor; the admission and exhaust are effected by the valves 7. These valves are parallel to the axis 8 of the engine, and the valve stems come level with a single plane 9 perpendicular to the axis 8.

The valve timing-gear of this engine is characterized by the fact that it is operated by a single cam-shaft 10, disposed perpendicular to the axis 8 of the engine and driven by a pair of helicoidal gear pinions 11.

This cam-shaft serves to drive the valves 7 which are individually designated in FIG. 2 by the letters A—B—C—D—E—F—G—H—I—J. There are provided several groups of similar controls common to a number of valves and shown in detail in FIGS. 3 to 5. Thus in the embodiment shown, the control which is the subject matter of FIG. 3 is common to the valves B, G, I, J and comprises for each

2

valve a V-shaped tongue 12, cooperating with a control rod 13 interposed between said tongue and a rocker 14 intended to actuate the corresponding valve.

The control which is the subject matter of FIG. 4 is common to the valves D and E and comprises for each valve a straight tongue 20 cooperating with a control rod 21 of a rocker 22 intended to actuate the corresponding valve.

FIG. 5 shows, on the one hand, a control common to the valves A and H comprising a tongue 23, a control rod 24, and a rocker 25 intended to actuate the corresponding valve and, on the other hand, a control common to the valves C and F comprising a tongue 26, a control rod 27 and a rocker 28 intended to actuate the corresponding valve.

The cam-shaft also carries the eccentric cam 15 which operates the fuel pump 16, and the shaft also drives directly from its two extremities the ignition device 17 and the oil-pump 18.

The advantage of this arrangement is that a single pair of pinions only is required to drive the cam-shaft, the ignition device, the oil-pump and the fuel pump.

I claim:

1. Improvements in the timing-gear of rotary explosion engines of the kind having a rotor with teeth rotating eccentrically in a toothed stator, comprising a cylinder head, lateral chambers in the head, a driving shaft, valves arranged in said chambers parallel to the axis of said driving shaft, a single cam-shaft having a plurality of cams affixed thereto, disposed perpendicular to the axis of the driving shaft, means driving said cam-shaft, control elements for the valves located at different distances from the cam-shaft and means of different lengths and forms acting on said control elements and actuated by the cams.

2. Improvements in valve timing-gear in accordance with claim 1, wherein said means driving said cam-shaft includes a single pair of pinions.

3. Improvements in valve timing-gear in accordance with claim 1, in which the engine also includes an ignition device and an oil pump and wherein said single cam-shaft also drives directly from its extremities, the ignition device and the oil-pump respectively.

4. Improvements in valve timing-gear in accordance with claim 1, in which the engine also includes a fuel pump that is also driven by an eccentric cam mounted on the said single cam-shaft.
